UNITED STATES PATENT OFFICE.

FRITZ PAFFRATH, OF SCHMALKALDEN, GERMANY.

FOLDING GRIDIRON.

1,130,760.

Specification of Letters Patent.

Patented Mar. 9, 1915.

Application filed April 8, 1913. Serial No. 759,773.

To all whom it may concern:

Be it known that I, FRITZ PAFFRATH, a subject of the King of Prussia, residing at Schmalkalden, in the Kingdom of Prussia, German Empire, have invented certain new and useful Improvements in Folding Grid-irons; and I do hereby declare the following to be a full, clear, and exact description of the invention, such as will enable others skilled in the art to which it appertains to make and use the same.

My invention relates to a folding grid-iron particularly adapted for sportsmen and the like.

15 Some illustrative embodiments of my invention are represented by way of example in the accompanying drawing wherein:—

Figure 1 is a side elevation showing one form of my gridiron opened out, Fig. 2 a 20 top plan view of the same, Fig. 3 an end elevation of the same showing one of the folding legs, and Fig. 4 a detail view showing portions of one of the legs.

Referring to Figs. 1 to 4, the gridiron 25 consists of three sections *a*, *b*, *c*. As seen in Fig. 2 each section comprises the two side-plates *d*, *d'* and two or more bars *e*. To stop the various sections *a*, *b*, *c* of the gridiron from being rotated too far when they are unfolded and fully laid out, the side-plates *d*, *d'* have lugs *f*, which fall into notches *g* in the adjacent side-plates.

When folding the sections of the gridiron together in the direction of the arrow *h*, 35 care must be taken that the various bars of the grid do not prevent the gridiron from being compactly closed. With this object, I provide in the narrowest section *a* the slots *i* extending from above and below to 40 the middle of the side plates, and in the section *b* the slots *i*, but only on the lower side; the widest section *c* contains none of such slots. When the section *a* is folded into the section *b*, the bars *e* in the latter enter into 45 the slots *i* on the lower side of the section *a*. The bars *e* in section *b* have slots *k* adjacent to the side-plates and extending to the middle of each bar, and consequently the side-

plates *d*, *d'* on section *a* can be completely folded into section *b*, the slots *i* and *k* which 50 by pairs correspond to each other will then engage one in another. The sections *a* and *b* thus folded together are then folded into the section *c*; the bars of the latter having somewhat wider slots *k*, and some of these 55 bars of section *c* are then located in the lower slots *i* in section *b* and others in the upper slots *i* in section *a*. In this manner the entire gridiron is compactly folded together. At each end of the gridiron there 60 are two folding legs *l*, which remain folded when it is desired to lay out the grid as shown in Fig. 2.

The outward movements of the two members *m*, *n* constituting a leg are limited in a 65 suitable manner by stops *o*, *p*, which, as seen in Fig. 4, may be formed by simply making cuts and bending over portions of the material forming the leg. In the illustrative embodiment the lower member is 70 shown unfolded outward somewhat farther than the upper one.

I claim:—

A folding gridiron comprising in combination a plurality of grate-shaped grids 75 pivotally connected at the ends thereof one to another, one of the side-plates of all the grids but one having a notch adjacent to the pivoted end thereof, and the adjacent end of each side-plate pivoted to a notched 80 side-plate having a lug adapted to engage in the adjacent notch when the gridiron is folded out rectilinearly, the side-plates of all the grids but one having notches for receiving the notches of the cross bars of the 85 grids in the folded position thereof, and the cross-bars of all the grids but one having notches for receiving the notches of the side-plates of the grids in the folded position thereof. 90

In testimony whereof I affix my signature in presence of two witnesses.

FRITZ PAFFRATH.
